UNITED STATES PATENT OFFICE.

EUGENE A. SPAULDING, OF PORTLAND, MAINE.

MACHINE FOR JOGGING PAPER AND THE LIKE.

Application filed April 14, 1924. Serial No. 706,448.

To all whom it may concern:

Be it known that I, EUGENE A. SPAULDING, a citizen of the United States, and a resident of Portland, in the county of Cumberland and State of Maine, have invented new and useful Improvements in a Machine for Jogging Paper and the like, of which the following is a specification.

This invention relates to novel improvements in a machine used for "jogging" paper, or other articles made in sheet form and which may be capable of being handled in a similar manner.

The word "jogger" and "jogging" signifies, as it is commercially used, the machine and process, respectively, for assembling a pile of sheets with at least two edges of all of the individual sheets in accurate alignment or register, and this meaning I shall apply to either term wherever it may appear throughout this specification.

In some forms of commercial printing, especially in lithographic or label work, large sheets of paper are employed, on each of which, multiple, and sometimes identical imprints are made. Afterward these sheets require to be cut up into units, and, as is generally the case, several hundred of these full size sheets are trimmed or cut simultaneously, it is obvious that very accurate alignment of every sheet in the pile on the cutter must be had,—else the resulting smaller sheets will not match or be identical.

Similarly, in color printing, where several separate imprints on the same sheet are made, and more especially where the press is equipped with an automatic feeder, the matter of close registration applies, as the sheets are generally jogged after each printing operation.

It is very difficult to properly "jog" by hand large sheets,—say 44 inches by 64 inches in size, which is a quite common commercial size, but with this power "jogger" the paper handling becomes a simple, efficient and expeditiously performed operation.

One of the objects of my improved machine is to provide a table, or support on which to lay the paper while being "jogged," which is capable of being adjusted to give a greater or less degree of incline to the sheets. As the weight and quality of the paper may vary greatly, so its treatment in "jogging" should vary accordingly, and it is important that provision should be

made to re-adjust the table to properly meet the changed conditions. The table on my machine may incline a certain number of degrees either to the right or left of horizontal, and while in the latter position greatly accommodates the work of unloading on to a truck on which to transport to the paper cutter.

Another object is to provide a supplementary table by dividing the original, integral one, transversely, and hinging the former on to cleats extending from under the latter. Thus equipped, the "jogger" has two independent tables employing two operators and handling the smaller size sheets very efficiently. The tables incline at reversed angles to each other.

A further object is to improve on the construction of the gauging parts. I mount adjustable gauges on the fence or top cleat of the table and this adjustability allows of duplicating the gauging points on the printing press. There are, generally, on the latter three gauging points,—two on the long side and one on the short side of the sheet being printed. If these points are similarly arranged on the "jogger" more accurate cutting results.

And a still further object is a greatly improved air hood on the feeding table. The function of this hood is to direct a blast of air under a moderate pressure into the pile of paper on the table, from off which it is taken and placed on the "jogger." This air blast serves two distinct purposes,—firstly, to "liven" up the sheets and in so doing assist the operator in culling them off the pile, and secondly,—to force a film of air between the sheets which greatly promotes the movement of the latter toward the gauges on the "jogger," after they have been transferred, several at each culling, from the feeding to the "jogging" table. It has been found impracticable, in a power "jogger," to properly handle large sheets without resort to this expedient.

An extended description of the machine to which these improvements apply, will, I believe, not be necessary at this time, as its construction in every detail has been disclosed in two United States patents,—one granted Sept. 24, 1918 and the other granted Oct. 8, 1918, the former numbered 1,279,493, and the latter 1,280,830; but descriptive matter concerning the above mentioned machine, sufficient to clearly connect

and coordinate the old with that which is new in my machine will be supplied, and this will serve to make an understanding of the present improvements more comprehensive.

In the drawings accompanying, and made a part of, this application,—

Fig. 1 is a side elevation of the "jogging" machine.

10 Fig. 2 an end elevation of the same.

Fig. 3 a perspective view of the feeding table, showing air hoods.

Fig. 4 is a plan of the "jogging" frame, without the table.

15 Fig. 5 is side view of the frame with an integral table.

Fig. 6 and Fig. 7 details of the actuating parts of the "jogger."

Fig. 8 and Fig. 9 are a side view and an 20 inverted plan, respectively, of a divided table.

Fig. 10 a section, taken on line 10—10, Fig. 8, and

25 Fig. 11 the same, but with the auxiliary table tilted and locked to make two independent tables.

Fig. 12 is a side elevation of the air hood.

Fig. 13 an end view of the inside nozzle.

Fig. 14 a plan, in part section, of the air 30 hood and inside nozzle, the section being taken on line 14—14, Fig. 12.

Fig. 15 a perspective view of the table (integral) showing the gauges.

Fig. 16 is a plan view of one of the gauges.

35 Fig. 17 is a section through the table and one of the gauges, and

Fig. 18 is a perspective of the paper weight.

Similar characters of reference refer to 40 similar parts throughout all the views in the drawings.

Referring to Figs. 1, 2 and 3, 1 is the base of the "jogging" machine, 2, 2 the end frames secured to said base by screws 3, 3. 45 Connecting the frames, and rigidly secured thereto, are shafts 4, 4. Mounted on these shafts (4) are spring supports 5, 5, from which rise helical springs 6, 6. The upper ends of these springs, which preferably are 50 four in number, are secured to the clamp housings 7, 7, which in turn are bolted rigidly to the "jogger" frame 8. Thus instead of securing these springs directly to the "jogger" table 9, I interpose the frame 8 and 55 this allows of independent means being employed to obtain a variable tilting or incline of the table, longitudinally,—the angle transversely being substantially the same at all times. More will be said concerning the foregoing hereinafter in this specification.

60 On the base 1 I mount a motor 10, driving, through the universal joint member 11, the pinion 12 which meshes with the gear 13 mounted on the shaft 14. A pinion, not shown, mounted on the shaft 14 adjacent the

gear 13, drives the gear 15,—the latter being the motive agent for the shaft 16, upon which are mounted the lateral cam 17 and the two radial cams 18. These cams, 17 and 18, 18, contact with the rolls 19, and 20, 20, 70 respectively, and give a longitudinal and transverse vibratory movement to the frame 8.

In direct connection with the motor shaft 75 is a blower 21, which furnishes a body of air under pressure to the air hoods, 22, 22, the latter mounted on the feed table which is a separate unit from the "jogging" machine, but is connected therewith by means of the air hose 23.

By reference to Figs. 4 and 5, 24 is a plate secured to the top side of the frame 8 and having a V shape, open top bearing 24'. Seated in this bearing is a strut 25, the flanged upper end of which is bolted to the under side of the table 9. At four points on the under side of the table are fixed arcuate arms 26 which extend downwardly and make a free contact with the inner sides of each of the projections 7' on the clamp 90 housings 7.

Two shafts 27, 27 extend through the projections 7', from side to side of the frame, with holding nuts on their outer ends, and having, for a spaced distance from their 95 ends, reverse hand screw threads cut thereon,—right hand on one side of the frame and left hand on the other. These shafts (27) are provided with clamping nuts 28, which at certain times are adapted to impinge on the inner faces of the arms 26. A short shaft 29, oscillatively mounted in the bearing 30, has a handle 31 on its outer end and carries a crank arm 32 fixed to its inner extremity.

Rigidly secured to the shafts 27 are crank arms 33, and pivotally connecting the latter with the crank arm 32 are connecting bars 34. It will thus be seen that, moving the handle 31 to the left will bind the arms 26 110 to the clamp housings 7, and, contrariwise, a movement of the handle to the right will release them,—the clamping nuts 28 being held against rotation by one of their sides 115 contacting with the housing 7. By loosening the nuts the table may be tilted or inclined a certain number of degrees either to the right or the left of horizontal, and when brought to the desired position may be rigidly locked. The bearing 24' serves as the 120 bearing point for the table.

It is often very convenient, as well as economical, when small size sheets are to be "jogged," to be able to utilize the "jogging" machine as a double-table "jogger." 125 For this purpose I divide the table 9 centrally, or thereabout, of its length and make provision for hinging the auxiliary portion to the main table through the agency of the hinges 35, 35,—securing the latter to the ex- 130

tended cleats 36, 36, projecting outwardly from the main portion of the table. To position and secure the auxiliary table 9' in any desired angle of incline I join the two tables by links 37, 37, pivotally connecting them to angle brackets 38 and 39 fixed on the table cleats 36 and 36' respectively. Fig. 10 shows the two tables locked in a position to be used as one long table, while Fig. 11 illustrates the auxiliary portion elevated and inclining at a reverse angle and locked so that the combination serves as a double table.

In Fig. 15 I show a one-piece table with the paper or sheet gauges in position. It will be understood, of course, that the table may be made as an integral structure and as such may be equipped so as to provide two compartments for "jogging,"—in contrast to the two entirely independent surfaces as shown in Figs. 8 and 9. In the illustration (Fig. 15) but one of these compartments is shown with gauges in place, but it is obvious that both may be so equipped. At 40 is a cleat, running lengthwise of the table 9, and secured thereto by wing nuts and screws 41, or other suitable means. Inside of, and fixed to this cleat is a "fence," or holding bar 42 for the gauges. At one end, and also at a central portion of the table, are transversely positioned cleats 43 having similar, although shorter, fences and identical securing means.

Operating on these fences, and adjustable to any position along their lengths, are gauges 44, the latter abutting on the inside faces of the fences to which they may be securely fastened by means of the clamps 45 and clamp screws 46. In a T slot 47 opening out from the inner faces of these gauges operate resilient paper weights 48 which are intended to assist in keeping the uppermost sheets in a subdued position and to aid materially in compacting the whole pile of sheets being "jogged." The vibratory action of the table releases these weights sufficiently to allow the incoming sheets to pass thereunder.

In Fig. 3 is seen the feed table 49, upon which at a spaced distance from the delivery end are mounted the air hoods 22. In Figs. 12, 13 and 14 is illustrated my improved air hood. I secure these hoods to the side edges of the feed table by proper means, as the screws 50, and provide clamping means 51 with which to attach the air hose 23 leading from the blower 21 on the "jogger." The outlet opening 52 from these hoods is contracted so as to produce a more powerful blast of air. Outside of, and in close proximity to, said opening are shutters 53, 53, frictionally secured to the pins 54, 54. To preclude the possibility of the sheets becoming entangled with the shutters I locate two pins 55, 55, outside the extreme arc of

action of the shutters, securing these pins to the extended base and top 22' of the hood.

At 56 is a bolt passing through the side of the hood 22 and adjustably clamping thereto the secondary nozzle 57. This 70 nozzle is shown in end elevation in Fig. 13, and in shape resembles somewhat the air hood itself. The exit for air from this nozzle is at 57' and its special function is to "wind" or air blast the very lower-most sheets in the pile. It overcomes the difficulty encountered when the air hood alone is used for this air blasting operation. Various expedients have been tried out with this single air hood in an endeavor to 80 achieve the results obtained by the use of this secondary nozzle, but baffle plates, irregular shaped exits etc., etc., resorted to have all failed to equal the combination as I now use it. With the air hood alone,—or used 85 as a primary nozzle,—the lower sheets in the pile would be compressed rather than separated,—due, most likely, to the arcing of the air in the hood, changing the direction of out-flow downwardly and thereby compacting the sheets.

In Fig. 3, in dot and dash lines, I have shown a pile of paper on the feed table, and have indicated in a somewhat exaggerated degree the effect the air blast has on the 95 sheets. To prevent the top sheets being wafted off the pile by the air blast I pivot on the cross bar 58 a plurality of weighted arms 59 adapted to lie loosely on the top sheet. The weight of these arms, however, 100 is not of a sufficient amount to hinder the operator in easily culling the sheets from the pile in the operation of placing them on the "jogging" machine.

Various slight changes may be made in 105 the general form and arrangement of the parts described without departing from the invention, and hence I do not limit myself to the precise details set forth but consider myself at liberty to make such changes and alterations as I may choose, provided, always, that the same shall fall within the spirit and scope of the appended claims.

Therefore, having thus described my invention, what I claim and wish to protect by 115 Letters Patent is:

1. In a machine for "jogging" paper and the like, the combination, with resiliently mounted sheet supporting means having a substantially constant angle of inclination 120 from horizontal towards one of its lateral edges and means for vibrating said supporting means in two right angularly disposed directions, of a frame, means for pivotally mounting said sheet supporting means on said frame, arcuate arms secured to and depending from said supporting means and adapted to slidably engage certain portions of said frame and means on said frame to lock said supporting means thereto in pre- 130

determined positions either horizontally or inclinable, lengthwise of said supporting means, to the right or left of horizontal.

2. In a machine for jogging paper or the like, the combination, with a resiliently mounted support for a pile of sheets and means for simultaneously vibrating said support in a lateral and longitudinal direction, of means for obtaining a predetermined

10 degree of inclination, longitudinally, of said

support, this inclination to be in conjunction with a substantially constant lateral inclination of the same, gauges on said support and adjusting means on said gauges whereby the gauging points for the sheets on said jogging machine may be similarly positioned, relatively, as the gauging points on a printing press from off which said sheets may have been taken. 15

EUGENE A. SPAULDING.
